UNITED STATES PATENT OFFICE.

JERRY PALMER, OF KORELOCK, MICHIGAN.

OAR-LOCK BUSHING.

1,264,848.

Specification of Letters Patent. Patented Apr. 30, 1918.

Application filed August 18, 1917. Serial No. 186,971.

To all whom it may concern:

Be it known that I, JERRY PALMER, a citizen of the United States, residing at Korelock, in the county of Ontonagon and State of Michigan, have invented certain new and useful Improvements in Oar-Lock Bushings, of which the following is a specification, reference being had to the accompanying drawings.

- 10 This invention relates to an improved oar lock bushing, and has for its primary object to provide a sectional bushing which may be easily and quickly inserted within the lock and around the oar shaft so that when 15 the oar is in operative position, all liability of the bushing sections being displaced or the possibility of the accidental displacement of the oar from the oar lock, is obviated.
- 20 It is another and more particular object of the invention to provide a bushing for oar locks consisting of two semicylindrical sections which are insertible within the lock upon the relatively reduced portion of the 25 oar shaft adjacent to the blade, the oar being subsequently moved longitudinally through the bushing sections to its operative position, urging the bushing sections apart, said sections being then rigidly fixed to the oar.
- 30 It is a further general object of the invention to provide a wear bushing for oars as above characterized, which is very simple in its construction, may be inexpensively manufactured, and is designed for use in connection with the ordinary form of open oar 35 lock.

With the above and other objects in view, my invention consists in the novel features of construction, combination, and arrangement of parts to be hereinafter more fully described, claimed, and illustrated in the accompanying drawing, in which,

Figure 1 is a perspective view illustrating the manner of arranging the bushing sections upon the oar within the oar lock;

Fig. 2 is a transverse sectional view showing the bushing sections secured to the oar in the operative position of the latter with respect to the oar lock; and

Fig. 3 is a section taken on the line 3—3 of Fig. 2.

Referring in detail to the drawings, 5 designates an oar lock of the ordinary open type generally used, having oppositely bowed arms spaced apart at their upper ends. With these arms, the central pin or shank

6 is integrally formed for engagement in the socket on the gunwale of the boat.

The improved wear bushing constituting the subject-matter of the present application, includes two similar sections 7 preferably in the form of brass castings, each of which has a body portion 8 of semi-cylindrical form and is provided upon its opposite ends with the outwardly projecting flanges 9.

S designates the shaft of the oar and B the blade thereof, and adjacent to the inner end of the blade, the shaft S is of reduced diameter, as shown at S'. In assembling the bushing upon the oar and within the oar lock, one bushing section 7 is first arranged in the lower portion of the oar lock 5 with its concave side facing upwardly and the flanges 9 disposed at opposite sides of the oar lock. The oar shaft S is now arranged in the lock with the reduced parts S' thereof seated upon the bushing section. The other bushing section is now inserted through the open side of the oar lock. It is to be noted that the body 8 of the bushing section is of a maximum diameter greater than the width of the oar lock opening and, therefore, it is necessary to move the bushing section into and through this opening by a circumferential movement. The diameter of the oar shaft portion S' is such as to permit of this turning movement of the bushing section through the open side of the oar lock until the longitudinal edges of said section are engaged upon the opposed edges of the other bushing section which was first arranged in the lock. The oar shaft is now forced longitudinally between the bushing sections so that the larger portion thereof will move between said sections and force the same in relatively opposite directions. When the oar shaft has been properly located with its handle in the desired position with respect to the oar lock, the two bushing sections are securely fastened to the oar shaft by means of the screws indicated at 10. It is, of course, understood that the sectional bushing is loose within the oar lock to enable the same to oscillate freely in the operation of the oar.

From the foregoing description, taken in connection with the accompanying drawing, the construction, manner of operation, and several advantages of the invention will be clearly and fully understood. By means of the device, wear upon the oar shaft is obvi-

ated, and when the oar is released, its retention in the oar lock is assured owing to the fact that the bushing is of such diameter that it cannot move outwardly through the open 5 oar lock. Thus, possibility of loss of the oar is obviated. The brass bushing also considerably strengthens the oar at its point of engagement in the lock so as to minimize liability of breakage of the oar. The oar 10 lock remains at all times in connection with the bushing and is carried with the oar when the oars are removed or arranged in operative position upon the boat. The device, while relatively simple in its construction, 15 has been found highly serviceable and convenient in practical use. It is also apparent that my improved oar lock bushing is exceedingly strong and durable and may be produced at relatively small manufacturing 20 cost.

While I have herein shown and described the preferred form and construction of the several features of the device, it is to be understood that the same are susceptible of 25 considerable modification and I, therefore, reserve the privilege of adopting all such legitimate changes as may be fairly embodied within the spirit and scope of the invention as claimed.

30 Having thus fully described my invention, what I desire to claim and secure by Letters Patent is:

1. The combination with an open oar lock, of a metal bushing consisting of two similar

sections each of semi-cylindrical form and 35 having a width greater than the opening of the oar lock, said bushing sections being adapted for insertion into the oar lock by a circumferential movement and upon the relatively reduced portion of an oar shaft adjacent to the blade, and the oar shaft being subsequently moved longitudinally between the bushing sections to a predetermined position with respect to the oar lock, and means 40 for rigidly securing the bushing sections to 45 the oar shaft.

2. The combination with an open oar lock, of a bushing consisting of two similar cast metal sections each of semi-cylindrical form and having outwardly projecting flanges on 50 its opposite ends, said bushing sections being of a width greater than the opening of the oar lock and adapted for insertion into the lock by circumferential movement through the open side thereof, said bushing sections being adapted for engagement upon the relatively reduced portion of the oar shaft adjacent to the blade and said shaft then moved longitudinally between the bushing sections 55 to a predetermined position with respect to the oar lock, and fastening screws to rigidly secure the bushing sections to the oar shaft. 60

In testimony whereof I hereunto affix my signature in the presence of two witnesses.

JERRY PALMER.
